UNITED STATES PATENT OFFICE.

STEPHEN C. MENDENHALL, OF RICHMOND, INDIANA.

CASTER.

SPECIFICATION forming part of Letters Patent No. 314,968, dated March 31, 1885.

Application filed February 25, 1885. (No model.)

To all whom it may concern:

Be it known that I, STEPHEN C. MENDENHALL, a citizen of the United States, residing at Richmond, in the county of Wayne and State of Indiana, (present business address 5 Cincinnati, Ohio,) have invented certain new and useful Improvements in Casters, of which the following is a specification.

The present improvements relate to casters for furniture and other articles in which the socket or furniture attachment and saddle or floor-wheel housing are made of wrought metal cut out or stamped into the form required. The advantage of such a method of making these parts of casters is that they can be made exceedingly light at little cost while possessing great strength. The floor-wheel of the improved caster is preferably made of glass with a floor-surface which is corrugated in the process of molding, so as to enable the roller to take a firmer hold upon the floor and aid the swiveling of the caster. It is necessary to provide a glass caster-roller with some form of bushing. This I preferably make of vulcanized fiber, wood, rubber, or other elastic material, a block of which is forced into the axial opening molded in the roller and then fixed by wedging out one end into a chamfer or notch provided in the body of the roller. 30 In order that the invention may be better understood, I will proceed to describe it with reference to the accompanying drawings, in which—

Figure I is a plan view of the housing or saddle blank as struck out ready to have its horns turned over. Fig. II is a similar view of the blank employed for making one part of the furniture-socket. Fig. III is a vertical sectional view of a mold for making my improved 35 floor wheel or roller. Fig. IV represents the roller in section with the tool employed for slitting one of the ends of the bushing to receive a wedge for holding the same in the roller. Fig. V is a sectional view of the floor roller complete. Fig. VI is a face view of the same. Fig. VII is a side elevation of a complete caster. Fig. VIII is a vertical section of the same. Fig. IX is a plan view of the saddle detached. Fig. X is a sectional view 40 through the furniture-socket, showing the horizontal anti-friction movement. Fig. XI is a side elevation of one of the parts of the fur-

niture-socket, the cap-plate being shown thereon in vertical section. Fig. XII is a vertical sectional view of the preferred form of the 55 furniture-socket as adapted for non-separating casters. Fig. XIII is a vertical sectional view of the saddle on the line XIII XIII, Fig. IX, omitting the floor-wheel axle.

In making my improved wrought caster I 60 cut a number of blanks of the shape shown in Fig. I, having two curved arms, 11, united at center by flat portion 2, which forms the top of the saddle, and in which is punched a hole, 3, for the spindle. At the same time 65 holes 4 in the ends of the horns 11 are punched, bulges 1^a are stamped in the arms 1 for strengthening same, and four little depressions, 5, are made in the flat top of the saddle for the purpose hereinafter set forth. The blank is then 70 forced into shape by turning down its horns 1 into the form shown in Figs. VII, VIII, IX.

The furniture-socket of the caster is made in two parts, the blanks therefor being prepared in the form shown in Fig. II in full 75 lines. These blanks are then stamped into the form shown in dotted lines in Fig. II and in full lines in Fig. XI, with a vertical barrel or socket, 6, having at bottom an enlarged chamber, 7, for the anti-friction rollers 8. 80 (Shown in Fig. X.) Vertical ridges 9, as shown in Figs. VII and XI, or spiral ribs 10, as shown in Fig. XII, may be struck in the socket at the same or a subsequent operation, these 85 ridges or ribs serving to hold the socket into the furniture when placed in position. In the form shown in Fig. XII, at the same or at a subsequent stamping operation, an external groove, 11, is made in the socket for the purpose of making an annular ridge, 12, on the 90 inside of the socket near its top for holding the spindle in position therein when the caster is put together. 13 is a rivet for holding the two parts of the socket together at the top. 14 is a cap-plate for holding the two parts of 95 the socket together at bottom, and at the same time retaining the horizontal anti-friction rollers 8 within the socket.

The spindle 15 of the caster is made with 100 spherio-segmental cavity for a hard metal anti-friction ball, 15^a, at its upper end, and with a shoulder, 16, near its lower end. 17 18 are two rectangular or other shaped plates or washers, so stamped as to have four little de-

pressions on one side and corresponding bosses on the other to engage with the bosses and depressions 5 in the saddle. This construction is shown most clearly in Fig. XIII.

- 5 In putting the caster together, one of the washers 17 18 is placed on each side of the saddle 2, and the same is slipped over the spindle until the upper washer, 17, strikes the shoulder 16. The bottom of the spindle is then riveted over the lower washer, 18, so as to hold saddle and spindle tightly together, the depressions and bosses 5 on the saddle and washers preventing any relative horizontal movement between these parts. The two parts 15 of the socket are then riveted together at top, the anti-friction rollers placed in position therein, and the cap-plate forced on the bottom, its edge being turned over the sides of chamber 7, as shown in Fig. VIII. The socket 20 and saddle are then ready to be put together, the ball 15^a being first dropped into the socket before the spindle is inserted therein. This is the method of putting the caster together when a separating caster is desired. In the case of 25 a non-separating caster, the spindle is provided with a groove near its top. (Shown in dotted lines in Fig. VIII.) In this case the rivet 13 is not employed to fasten the two parts of the top together until the spindle is in position within the socket; or, if the socket be 30 first riveted, the spindle may be forcibly driven in until its head comes beyond the ridge 12, (shown in Fig. XII;) or the said ridge may be struck in the top after the spindle is in position, so as finally to hold the spindle in the socket.

In Fig. X I have shown the horizontal anti-friction rollers 8 made of sections of tubing; but it is obvious that they may be made solid 40 by being cut off of solid metallic rods.

The glass floor-roller is cast in the mold shown in Fig. III, the principal parts of which have been described in my former application No. 154,377, filed January 29, 1885. As herein shown, however, the jaws of said mold are made with horizontal corrugations 19, which form similar corrugations on the otherwise flat bearing-face 20 of the floor-roller. An axial opening is made in the roller in the process of 45 molding, and such opening is subsequently bored or ground out to provide a cylindrical or slightly-tapering bearing for a bushing, 21, of vulcanized fiber, wood, rubber, or other suitable material. At one or both ends the 50 axial opening is slightly enlarged or cham-

fered, and the bushing is slotted and spread into this chamfer by means of the tool 22. (Shown in Fig. IV.) Said tool has a cylindrical centering-pin, 23, for occupying the bearing within the journal, and a sharpened 60 wedge, 24, for forming a circular slit in the bushing at one or both ends. In such slit a ring-shaped or other wedge, 25, is driven, thus forcing the outer part of the bushing to spread and occupy the chamfer in the roller, 65 and thus prevent the bushing from loosening and falling out. Said wedges may be provided at each end of the bushing, or one end may be slightly smaller than the other, and in this end alone such wedge would then be 70 necessary.

It is observable that the corrugated or roughened face of the floor-roller will adapt it to take firm hold on the carpet or floor, so as to prevent sidewise movement of the roller over the 75 carpet and force the same to swivel about the vertical spindle. Such construction also renders the roller applicable to skates for the same reason—namely, the preventing of the lateral movement of the roller upon the floor. 80

Having thus described my invention, the following is what I claim as new therein and desire to secure by Letters Patent:

1. In a caster, a wrought socket or top stamped out in two parts, having ridges or ribs 85 stamped therein for holding the socket within the furniture, substantially as set forth.
2. A wrought socket or top for casters having an annular depression stamped around it near its top, forming an internal ridge for retaining the spindle in place, substantially as set forth. 90
3. In combination with a wrought saddle, washers on each side of the same, and corresponding depressions and bosses in the saddle 95 and washers, for preventing relative horizontal movement between these parts, substantially as set forth.
4. A floor wheel or roller made with circumferential corrugations, substantially as and for 100 the purpose set forth.
5. In combination with a floor wheel or roller having axial opening, chamfered or recessed, as described, a bushing therefor, and a wedge for forcing said bushing into the chamfer or recess, for the purpose set forth. 105

STEPHEN C. MENDENHALL.
